UNITED STATES PATENT OFFICE.

FRED L. GREGORY, OF CHICAGO, ILLINOIS.

ROTARY MOTOR.

No. 856,631.

Specification of Letters Patent.

Patented June 11, 1907.

Application filed October 30, 1905. Serial No. 285,108.

To all whom it may concern:

Be it known that I, FRED L. GREGORY, a citizen of the United States, residing at Chicago, in the county of Cook and State of Illinois, have invented a new and useful Improvement in Rotary Motors and Pumps, of which the following is a specification.

My invention relates particularly to rotary motors, although it will be understood that certain features of the invention are applicable to rotary pumps and compressors.

The primary object of my invention is to provide a rotary motor of improved general construction, particular attention being paid to securing adequate packing of the joints and improved admission and exhaust mechanism.

The invention is illustrated in its preferred embodiment in the accompanying drawings, in which—

Figure 1 represents a vertical section of my improved motor, the section being taken as indicated at line 1 of Fig. 4; Fig. 2, a perspective view of certain packing-members employed in connection with the vanes; Fig. 3, a perspective view of one of the vanes adapted to receive the packing-members shown in Fig. 2; Fig. 4, a section taken as indicated at line 4 of Fig. 1; Fig. 5, a perspective view of a manually-controlled valve employed; Fig. 6, a broken outer face view of the cylinder-end adjacent to the valves employed; Fig. 7, a broken sectional view taken as indicated at line 7 of Fig. 4; Fig. 8, a section similar to Fig. 7, but of less extent, the manually-actuated valve being shown in the position it occupies in starting the engine; and Fig. 9, a similar section, the manually-actuated valve being shown in the position which it occupies during the normal operation of the motor.

In the construction shown, A represents a stationary cylinder supported on a base A¹ and equipped with removable ends A², A³; B, a shaft journaled in the cylinder-ends and equipped with vanes B¹, B²; B³, an annular rotary piston anti-frictionally journaled on annular race-members a adjustably connected with the inner surfaces of the cylinder-ends and eccentrically set with relation to the shaft B; B⁴, packing devices connected with the vanes; and C, valve mechanism connected with the shaft and one of the cylinder ends.

The casing, or cylinder, may be of any suitable construction. Preferably, it has the removable ends; and the ends are provided with bolts a¹ having screw connection with

both the cylinder ends and rings a, and screws a² alternating with the bolts a¹ and serving to force the rings a inwardly in the adjustment for wear. As shown, the rings a support balls a³ contacting with cones a⁴ forming a part of or connected with the ends of the annular piston B³. The annular piston has contact at its lower side with an adjustable section a⁵ at the base of the cylinder, the section a⁵ being supported by a spring a⁶, the tension of which is regulated by a screw a⁷ accessible from the exterior of the base of the cylinder.

The shaft B is concentric with the bore of the cylinder and eccentric with the annular piston. One of the piston members, or vanes, is firmly secured on the shaft, thereby to impart motion to the shaft, and the other is pivoted on the shaft to permit the angular movement which necessarily occurs during the rotation of the piston. Each vane preferably comprises a plate b, and a hub-portion b¹ for connection with the shaft. The plate is provided with a slot b² which receives the movable packing device B⁴. Each device B⁴ comprises a member b³ fitting within the slot b² at the outer or free end of the vane; members b⁴ fitting within the slot b² at the lateral edges of the vane; pivotally connected links b⁵ having their free ends engaging slots b⁶ in the members b⁴; and a follower b⁷ located in the socket b⁸ with which the vane is provided centrally at the bottom wall of the slot, the follower being projected by means of a spring b⁹. The follower acts upon the links b⁵ at the point of pivotal connection between said links, thereby tending to force the members b⁴ against the cylinder ends and also to force them outward longitudinally, thereby to maintain the member b³ in close contact with the inner cylindrical surface of the casing.

As shown in Fig. 2, the meeting ends of the members b⁴ and the member b³ have a mortise and tenon connection of a character to permit the members b⁴ to separate, while the shoulders at the bases of the tenons serve to transmit thrust from the members b⁴ to the member b³, thereby providing for the maintenance of perfect joints, regardless of wear.

As clearly shown in Fig. 1, the vanes B¹, B² preferably pass through rocking bearings or packing members b¹⁰ with which the core or annular piston B³ is provided, said members being held in close contact with vanes by springs b¹¹ confined in suitable sockets with

which the annular piston is provided. As clearly appears from Fig. 4, the cylinder ends are bored out somewhat on their inner sides to receive the ends of the annular piston member, and packing-rings b^{12} are provided between the circumferential surfaces of the cylinder ends and the adjacent circumferential portions of the annular piston.

The valve mechanism C comprises a manually-operated valve c in the form of an annular disk or ring fitting upon a hub c^1 with which the cylinder end A^2 is provided, said disk being joined by arms c^2 to a sleeve c^3 fitting on the shaft B and equipped with an actuating-arm c^4 ; a shaft-actuated valve c^5 located at the outer side of the valve c and secured on the shaft B to rotate therewith; and a valve-casing c^6 fitting on the sleeve c^3 and having an external flange c^7 at its inner end which is firmly secured to the cylinder end, so that there is provided between the cylinder end and the member c^6 a valve chamber c^8 . The main casing is provided at its base with chambers c^9 which flank the adjustable section c^5 of the cylinder and communicate with the interior of the cylinder through passages c^{10} . The cylinder end A^2 is provided with ports c^{11} , c^{12} which communicate with the chambers c^9 , and which terminate at the outer surface of the cylinder end A^2 in enlargements c^{13} . The cylinder-end A^2 is further provided with an exhaust passage c^{14} , as shown in Figs. 4 and 6. The valve-disk c is provided on its inner face at its lower portion with a channel c^{15} , which serves to place either one of the ports c^{11} , c^{12} in communication with the exhaust port c^{14} , at will. It is further provided on opposite sides of the center of its upper portion with circumferential recesses or ports c^{16} , and below said ports and on a shorter radius with smaller ports or apertures c^{17} . The upper end of the arm c^4 is turned inwardly and equipped with a spring-held catch c^{18} , which may be caused to engage any one of a series of sockets c^{19} , c^{20} , c^{21} , c^{22} , c^{23} provided in the outer surface of the upper portion of the cylindrical part of the valve-casing c^6 . The sleeve c^3 is preferably provided with a packing-gland c^{24} as shown. The disk-valve c^5 is of smaller diameter than the valve c , and is provided at diametrically opposite points with elongated circumferential recesses or ports c^{25} , c^{26} .

From the foregoing description, the manner of use will be readily understood. Steam or fluid under pressure is admitted to the valve-chamber c^8 through a pipe d . The valve c , through the medium of its handle c^4 , is turned in one direction or the other, according to the direction of rotation of the piston desired, to bring one of the ports c^{16} into registration with the port c^{11} or c^{12} , according to the direction of rotation desired. This admits fluid to the cylinder, regardless of the position of the shaft-actuated valve c^5 .

After the piston is in motion, the valve c may be turned back toward its initial central position of neutrality, thereby to throw the port c^{16} out of registration with the port in the cylinder end, and throw the adjacent port c^{17} into registration with the port in the cylinder end, in either of which positions the valve c will permit exhaust to take place. For illustration, the catch c^{18} may be withdrawn from the socket c^{20} shown in Fig. 4, and the valve c turned from the neutral position shown in Figs. 4 and 7 to the starting position shown in Fig. 8, in which position the catch c^{18} will engage the socket c^{20} shown in Fig. 7. In this movement, one of the ports c^{16} is brought into registration with the port c^{11} , and the port c^{15} is brought in position to connect the port c^{12} with the exhaust port c^{14} . After the piston is in motion, the handle c^4 may be turned to bring the catch c^{18} into engagement with the socket c^{21} , and corresponding with this position, the valve c will have one of its ports c^{17} in registration with the port c^{11} , as shown in Fig. 9, while the exhaust port c^{15} will still connect the port c^{12} with the exhaust port c^{14} . As the piston rotates now, it will intermittently close and open the port c^{11} , providing for admission and expansion of steam, where steam is used as the motive fluid. It will be understood, without further explanation, that the direction of rotation may be reversed by turning the valve c initially in the direction opposite that just described. In operation, the weight of the piston is carried on the anti-friction bearings, and as the packing members at the lateral and outer edges of the vanes wear, they are automatically adjusted to maintain a close joint. In the event that a looseness develops at the anti-friction bearings, the cap-screws a^1 may be unturned somewhat and the screws a^2 turned inwardly to force the race-members a inwardly, thereby locking them securely.

It will be understood that no undue limitation is intended by the foregoing detailed description, inasmuch as changes in details of construction within the spirit of the invention may be made.

What I regard as new, and desire to secure by Letters Patent, is—

1. The combination of a casing, a rotary piston, a vane connected with said piston, lateral-edge and side-edge packing-members connected with the lateral and outer edges of said vane and having overlapping portions slidable upon each other at the outer corners of the vane, and a spring serving normally to force said lateral-edge packing-members into close contact with the ends of the cylinder and serving also, through the medium of said lateral-edge packing-members, to force the end-edge packing-member into contact with the inner cylindrical surface of the cylinder.

2. The combination of a casing, a rotary

- piston, a vane connected with said piston, an end-edge packing member connected with said vane, lateral-edge packing members connected with said vane and serving to 5 transmit thrust to the end-edge packing member, links connected with said lateral-edge packing members, and a spring-projected follower serving to transmit thrust through said links, for the purpose set forth.
- 10 3. The combination of a stationary cylinder, a rotary piston, said cylinder being provided with admission and exhaust ports, and a manually-actuated valve and a power-actuated valve having ports which may be brought into registration with the ports of the cylinder, the manually-actuated valve having additional ports for use in starting the engine, for the purpose set forth.
- 15 4. The combination of a stationary cylinder having an end provided with admission and exhaust ports, a rotary piston having a shaft extending through said end, a valve carried by a sleeve journaled on said shaft and equipped with a controlling handle, a valve 20 located outside said first-named valve and actuated by said shaft, and a valve-casing forming with said cylinder-end a chamber for the valves, said sleeve extending through the valve-casing and having its actuating 25 handle connected with its outer end, for the purpose set forth.
- 20 5. The combination of a stationary cylinder having an end provided with admission and exhaust ports, a shaft extending through said end, a rotary piston connected with said shaft, a valve controlling said ports and equipped with a tubular stem journaled on said shaft, a valve-casing having an end in which said tubular stem is journaled, said valve casing being provided with a plurality 30 of sockets, an arm connected with said stem and equipped with a catch adapted to engage said sockets, and a valve actuated by said shaft and co-acting with said first-named valve, for the purpose set forth. 35
- 25 6. The combination of a stationary cylinder having an end provided with admission and exhaust ports, a shaft extending through said end, a rotary piston connected with said shaft, a manually-actuated valve having a 40 face located adjacent to the outer surface of said cylinder end, said valve having an exhaust passage at its inner face and having circumferential starting admission ports and additional ports located within a smaller 45 radius, and a valve adjacent to said first-named valve and actuated by said shaft, said last-named valve being of smaller diameter than the first-named valve and controlling said last-named ports of said first-named 50 valve, for the purpose set forth. 55

FRED L. GREGORY.
